UNITED STATES PATENT OFFICE

BRADFORD T. BORDEN, OF CLEVELAND, OHIO, ASSIGNOR OF ONE-HALF TO WILLIAM A. NERACHER, OF WARREN, OHIO, AND ONE-HALF TO THE BORDEN COMPANY, OF WARREN, OHIO, A CORPORATION OF OHIO

WORKHOLDER FOR DIESTOCKS AND THE LIKE

Application filed January 9, 1930. Serial No. 419,633.

My invention relates to improvements in work holders for die stocks and the like.

Briefly stated, the invention has for one of its primary objects to provide a novel and improved device of this kind which establishes a very effective bearing contact with the work to prevent rocking or shifting of the tool relative thereto.

An object of the present invention is to provide a work holder which will have all of the advantages of the interchangeable bushings, such as are commonly used to engage the work at an axially spaced point from the dies or other work engaging elements,—and which has an added advantage over such bushings in that no removal of parts is necessary when changing from one standard size of work to another standard size.

A further and more specific object of the invention is to provide a work holder for die stocks and the like comprising a pair of opposed rotatable elements having corresponding edge recesses adapted to be brought into opposition with one another for engaging the different standard sizes of work with which the die stock or other tool will be used,—the nature of the construction being such that the work engaging elements may remain secured to the tool at all times, thus obviating the likelihood of their being lost.

The invention also contemplates a work holder as set forth, which comprises a minimum number of very simple and durable parts of inexpensive construction,—the device being easy to assemble, convenient to use and capable of ready application to standard die stocks and similar tools without substantial modification thereof.

The invention also resides in certain novel features of construction, combination and arrangement of the various parts, and in certain modes of operation, all of which will be readily understood and appreciated by those skilled in the art upon reference to the accompanying drawings in connection with the following descriptive matter.

The drawings illustrate what is now regarded as a preferred embodiment of the invention, but it is to be understood that the same is capable of other mechanical expres-

sions within the spirit and scope of the subject matter claimed hereinafter.

In the drawings,

Figure 1 is a bottom perspective view illustrating the application of my invention to a die stock;

Figure 2 is a top plan view of the device showing a piece of pipe in cross section;

Figure 3 is a cross sectional view through one of the rolls of Figs. 1 and 2; and

Fig. 4 is a fragmentary side view of one of the spring bearing elements.

Referring specifically to the drawings, wherein the same reference characters have been used to designate the same parts in all views, numeral 10 denotes a die stock which may be of the usual or any preferred form having the customary work receiving opening into which project the chasers 20. The die stock being provided, of course, with the conventional handle sockets 30.

In the drawings it will be noted that I have illustrated a preferred embodiment of the invention wherein a removable work-holder 55 is shown having a neck portion 56 adapted to be inserted into the neck portion 57 of the die stock and secured therein by means of a thumb screw 58 extending through the neck portion of the die stock and adapted to engage in a recess in the exterior portion of the neck portion of the work-holder.

The work-holder of Fig. 1 comprehends a flanged frame having bearings 60 for the pintles 61 of a pair of opposed horizontally journaled rolls 62 whose peripheral surfaces are provided with cutouts of arcual form, as indicated at 63, to overlie the work-receiving hole 65 so as to embrace the work to provide a bearing so that the die stock and work-holder assembly can be rotated relatively of the work in the threading operation.

The frame of the work-holder 55 is provided with small cylindrical portions 67 threaded therethrough and carrying a spring pressed bearing element 69 adapted to enter recesses 70 formed in the ends of cylinders 62, whereby to tend to hold the same in a set position. Numeral 71 designates size indi-

cating marks adjacent the respectively recess portions 63 of the cylinders.

The two adjacent cutouts 63 form, as will be clearly seen from Fig. 2, bearing surfaces for a pipe, which is to be cut or threaded.

The work will be very effectively engaged and supported by the two rolls, the bearing surface being the whole length of a chord of the circumference of the roll, as shown in Fig. 3. It will be manifest also that it will be a very simple matter to rotate each roll to effectively support different sizes of standard work. The rolls being held in position by the spring actuated ball member 69.

Having thus described my invention, what I claim as new and desire to secure by Letters Patent is:

1. In a pipe guide for pipe working tools, the combination of a frame, a pair of cylinders mounted therein on opposite sides of the pipe axis and on axes parallel with each other and transverse of the pipe axis, each cylinder having a plurality of notches in its periphery, the notches in each cylinder being of different depth and each of them having curved edges whereby cooperating notches may define different pipe receiving openings.

2. A self-contained pipe guide adapted for removable mounting on a die stock, comprising a frame having a neck to telescope with the die stock, and an open border, a pair of rollers journaled in said border on axes transverse to the die stock axis, said rollers having a series of peripheral notches of different depth.

3. The combination with a die stock having an annular frame and cutters, of a work holder at one end of the die stock having a rectangular border frame with walls extending in the general direction of the length of the pipe to be threaded, a pair of rollers mounted on parallel transverse axes on opposite sides of the pipe axis, said rollers being journaled in the opposite walls of the frame and lying partly in the space between the frame walls, said rollers having formed in them notches of varying depth with their bottoms forming chords of the circular contour of the roller.

4. A work holder for die stocks, comprising a frame having an opening for the passage of a pipe and a projecting flange in the form of an open quadrangle, and a pair of rollers mounted between the opposite sides of said flange and journaled on axes which are transverse to the pipe opening, said rollers having notches at varying depths in their peripheries.

5. A work holder for die stocks, comprising a frame having an opening for the passage of a pipe and a projecting flange in the form of an open quadrangle, a pair of rollers between the opposite sides of said flange rotatably carried by pins mounted in the

flange on axes which are transverse to the pipe opening, each roller having notches at varying depths in its periphery, and means carried by the flange for engaging the rollers and retaining each of them in any of a plurality of selected positions.

In testimony whereof I affix my signature.

BRADFORD T. BORDEN.
